(57) CLAIM

The ornamental design for a trellis post, as shown and described.

DESCRIPTION

FIG. 1 is a front perspective view of a first embodiment of a trellis post embodying the present invention, having two rows of apertures;

FIG. 2 is a front elevational view of FIG. 1;

FIG. 3 is a rear elevational view of FIG. 1;

FIG. 4 is a right side view of FIG. 1; the left side being a mirror image thereof;

FIG. 5 is a front perspective view of a second embodiment of a trellis post embodying the present invention, having two rows of apertures that are differently spaced;

FIG. 6 is a first end view of FIGS. 1 and 5, the other end view being a mirror image thereof; and,

FIG. 7 is an enlarged partial view of one of the apertures of FIGS. 1 and 2.

Except for the differences shown in the spacing of the apertures in the two rows in the front perspective views, the second embodiment is the same in appearance as the first embodiment. The trellis post is broken to indicate indeterminate length.
